UNITED STATES PATENT OFFICE

WILLIAM A. NOSIK, RUDOLPH J. NOSIK, JOHN S. KROCKA, AND WALTER MONCHER,
OF MILWAUKEE, WISCONSIN

PAJAMAS

Application filed September 16, 1932. Serial No. 633,518.

The present invention relates to pajamas and more particularly to new and useful improvements in beach pajamas and has for its primary object to provide, in a manner as hereinafter set forth, a garment of this character embodying a novel construction, combination and arrangement of parts through the medium of which a neat and attractive appearance will be maintained at all times and 10 damage to upholstery, as in automobiles, and furniture by water will be prevented when the garment is worn over a wet bathing suit.

Other objects of the invention are to provide a garment of the aforementioned character which will be simple in construction, 15 strong, durable, light in weight and which may be manufactured at low cost.

All of the foregoing and still further objects and advantages of the invention will 20 become apparent from a study of the following specification, taken in connection with the accompanying drawings wherein like characters of reference designate corresponding parts throughout the several views, and 25 wherein:—

Figure 1 is a view in front elevation of an embodiment of a garment constructed in accordance with the present invention.

Figure 2 is a view in rear elevation thereof.

Figure 3 is a detail view in elevation of 30 one of the trouser members.

Figure 4 is a detail view in perspective of the trunk portion of the garment.

Figure 5 is a detail elevational view of the 35 other trouser members.

Referring now to the drawings in detail, it will be seen that the embodiment of the invention which has been illustrated comprises a trunk portion 1 of suitable flexible 40 water-proof material to the top of which a bodice portion 2 of any suitable material and design is stitched, as at 3. The form of the bodice portion 2 which has been illustrated comprises a pair of pieces of material which 45 are formed to provide shoulder straps and arm openings, said pieces being lapped and secured, at their lower portions, to the trunks 1.

The reference numeral 4 designates the 50 trousers members of the garment which are

of suitable flexible water repellent material. The bifurcations or leg portions of the trunks 1 extend into the upper portions of the trousers members 4 and are stitched thereto, as at 5. In the embodiment of the invention which has been shown, the trousers members 4 include substantially tapered front and rear extensions 6 which extend to the top of the trunks 1 and are secured thereto. The extensions 6, in addition to lending attractiveness to the garment, also constitute strengthening or reinforcing means. The trousers members 4 terminate in cuffs 7 at their lower ends.

It will thus be seen that a beach pajama has been provided which, because of the materials from which the various portions are constructed, will maintain a neat and attractive appearance substantially at all times, and which will prevent damage to upholstery in automobiles and furniture when the wearer sits thereon should the garment be worn over a wet bathing suit. The water-proof trunk portion 1 positively prevents the passage of water or moisture at this point in 55 the garment while the water repellent trousers members 4 constitute drains for the water which may drip from a wet bathing suit over which the garment is being worn.

It is believed that the many advantages 60 of a garment constructed in accordance with the present invention will be readily understood, and although the preferred embodiment of the invention is as illustrated and described, it is to be understood that changes 65 in the details of construction and in the combination and arrangement of parts may be resorted to which will fall within the scope 70 of the invention as claimed.

What is claimed is:—

1. A beach pajama comprising a trunk portion of flexible, water-proof material, a bodice portion of flexible material secured to the trunk portion, and trousers members of flexible, water repellent material telescopically receiving the legs of the trunk portion and secured to the trunk portion at the ends of the legs and at the waist line of the trunk portion.

2. A beach pajama comprising a trunk por- 100

- tion, a bodice portion secured at the waist line to the trunks portion, trousers members secured to the leg portions of the trunk portion, said leg portions of the trunk portion extending into the upper portions of the trousers members, and extensions on the front and rear of the upper ends of the trousers members extending substantially to the waist line of the trunk portion and secured thereto.
- 5 3. A beach pajama comprising a trunk portion of flexible, water-proof material, a bodice portion of flexible material stitched, at its bottom, to the top of the trunks portion, trousers members of flexible, water repellent material depending from the leg portions of the trunk portion, said leg portions of the trunk portion extending into the upper portions of the trousers members and being stitched thereto, and substantially tapered
- 10 front and rear extensions rising from the upper ends of the trousers members and extending over the trunks portion to the top thereof and secured thereto.
- 15
- 20

In testimony whereof we affix our signatures.

25 WILLIAM A. NOSIK.
RUDOLPH J. NOSIK.
JOHN S. KROCKA.
WALTER MONCHER.
